UNITED STATES PATENT OFFICE.

JOSEPH A. GAGNON, OF FITCHBURG, MASSACHUSETTS, ASSIGNOR TO CROMPTON & KNOWLES LOOM WORKS, OF WORCESTER, MASSACHUSETTS, A CORPORATION OF MASSACHUSETTS.

CENTER-FILLING STOP-MOTION FOR LOOMS.

1,243,831.

Specification of Letters Patent.

Patented Oct. 23, 1917.

Application filed February 24, 1916. Serial No. 80,283.

To all whom it may concern:

Be it known that I, JOSEPH A. GAGNON, a citizen of the United States, residing at Fitchburg, in the county of Worcester and State of Massachusetts, have invented a new and useful Center-Filling Stop-Motion for Looms, of which the following is a specification.

This invention relates to certain improvements in a center filling stop motion for looms.

It is the general object of my invention to improve the construction of such stop motions to the end that they may be more efficient and reliable in operation and that they may be less liable to breakage of parts.

With this general object in view my invention relates to certain arrangements and combinations of parts which will be herein-after described and more particularly pointed out in the appended claims.

A preferred form of my invention and a modification thereof are shown in the drawings in which—

25 Figure 1 is a side elevation of one form of my improved stop motion;

Fig. 2 is a top plan view thereof;

30 Figs. 3, 4 and 5 are partial side elevations similar to Fig. 1 but showing the parts in different positions; and

Fig. 6 is a partial side elevation of a modified form of my invention.

Referring to Figs. 1 to 5, I have indicated the lay of the loom at 10 and a portion of the breast beam at 11. The usual shipper rod 12 is carried in brackets 13, secured to the breast beam 11 and is provided with an arm 14 extending rearwardly therefrom. The arm 14 is positioned for engagement by an actuating lever 15 pivoted at 16 to a stand 17 which in turn is bolted to the breast beam 11.

45 A center filling fork 18 of the usual type is mounted upon the casting 19 carried by the lay 10 and is connected by a link 20 to an arm 21, pivoted at 22 to a projection 23 formed on the casting 19. A dagger 24 is adjustably secured in the arm 21, said dagger at times cooperating with the actuating lever 15 to move the shipper rod 12 and thus stop the loom through connections not shown. The dagger 24 normally rests upon a cam plate 25 adjustably secured by a slot and bolt connection 26 to the stand 17.

55 When the loom is in its normal condition

of operation the parts are in the condition shown in Fig. 4. If the filling is then broken or exhausted the filling fork 18 will be unsupported and the dagger 24 will move downward along the cam plate 25 as the lay 60 moves forward. During such forward movement the dagger will engage the notched end of the actuating lever 15, moving the lever forward to throw the shipper.

The permissible movement of the shipper 65 rod is limited and the stop 27 is provided for correspondingly limiting the movement of the lever 15. The lever 15 will engage the stop 27 before the dagger reaches its forward limit of travel and it is therefore necessary to disengage the dagger from the lever while the dagger is still moving forward. For this purpose I provide the cam roll 28, pivoted at 29 to the stand 17. As the dagger moves forward in engagement with 70 the actuating lever 15, it will engage the roll 28 and will be raised thereby, being thus disengaged from the lever 15 as shown in Fig. 5.

The formation of the cam in the shape of 80 a roll aids materially in separating the dagger and lever with a smooth and easy motion but this form of cam is not absolutely essential. I have substituted a cam shaped projection 280 upon the stand 17 in place 85 of the cam roll 28 in the modified form shown in Fig. 6 and many of the advantages of my invention may be attained by the use of this modified construction.

After the loom has been stopped by break- 90 age or failure of filling, it is ordinarily necessary for the lay to beat up once without any filling in the shed and it is necessary to prevent the operation of the stop motion during this first beat of the lay after a new 95 bobbin has been inserted. For this purpose a shield 30 is mounted upon the side of the stand 17, the shield being provided with inclined slots 31 through which extend studs 32 by which the shield is retained in position.

At its left hand end as viewed in Fig. 1, the shield engages one arm 33^a of a two-armed lever 33. The lever 33 is pivoted at 34 on the stand 17 and the second arm is 105 provided with a stud 35 positioned for engagement by a flat spring 36 secured to and movable with the shipper rod 12. As the shipper is thrown off the spring 36 is moved downwardly, engaging the stud 35 and thus 110

turning the lever 33. During such turning movement the arm 33^a by its engagement with the end of the shield 30, moves the shield to its raised or operative position as shown in Fig. 1.

When the shipper is again thrown on, the spring 36 will be raised from the stud 35 but the lever 33 and shield 30 will be retained by friction in the position shown in Fig. 3, the lever 15 being simultaneously moved to position for engagement with the dagger 24.

As the lay thereafter moves forward upon its first beat after the replenishing of the filling, the absence of filling in the shed will permit the fork 18 to move downward and the dagger 24 will follow the cam plate 25 until it engages the upper edge of the shield 30. Such engagement however, will cause the dagger to pass over the end of the actuating lever 15. As the dagger approaches the forward end of its path of travel it will engage a projection 30^a upon the shield 30 and will force the shield backward and downward to the position shown in Fig. 4.

The loom will thereafter operate in the usual manner until a failure of filling, when the dagger will engage the lever 15 and stop the loom as has been previously described.

The provision of the cam roll 28 or the cam surface 280 permits earlier engagement and disengagement of the dagger 24 and the lever 15 and this is found to be of substantial advantage in certain looms in which it is impossible to turn the loom backward after the lay has reached a certain position in its forward movement. By the earlier engagement of the dagger with the actuating lever the limits of movement of the lay after such engagement are correspondingly increased and the brakes may be permitted to act more gradually. This gradual application of the brakes has been found in practice to noticeably reduce the breakage of gear teeth and other parts, due to the sudden stopping of the loom.

Having thus described my invention, it will be evident that other changes and modifications can be made therein by those skilled in the art without departing from the spirit and scope of my invention as set forth in the claims and I do not wish to be otherwise limited to the details herein disclosed but what I claim is:—

1. A center filling stop motion for looms comprising a shipper rod, an arm on said rod, a fixed stand, a lever pivoted on said stand and engaging said arm to actuate the shipper, a filling fork and dagger mounted on the lay, said dagger being connected to said filling fork and being adapted to nor-

mally engage and actuate said lever, a shield movable into position to cover the end of said lever in all positions thereof, means for moving said shield into and out of operative position, and a cam effective to raise the dagger out of engagement with said lever when the dagger reaches a predetermined point in its forward movement.

2. A center filling stop motion for looms comprising a shipper rod, an arm on said rod, a fixed stand, a lever pivoted on said stand, and engaging said arm to actuate the shipper, a filling fork and dagger mounted on the lay, said dagger being connected to said filling fork and being adapted to normally engage and actuate said lever, a shield movable into position to cover the end of said lever in all positions thereof, means for moving said shield into and out of operative position and a cam mounted on said stand and effective to easily and quickly raise said dagger out of engagement with said lever as the dagger reaches a predetermined point in its forward movement.

3. A center filling stop motion for looms comprising a shipper rod, an arm on said rod, a fixed stand, a lever pivoted on said stand, and engaging said arm to actuate the shipper, a filling fork and dagger mounted on the lay, said dagger being connected to said filling fork and being adapted to normally engage and actuate said lever, a shield movable into position to cover the end of said lever in all positions thereof, means connected with said shipper rod for moving said shield into position to cover said lever, a projection on said shield positioned for engagement by said dagger on its idle stroke, by which engagement said shield is removed from operative position, and a roll mounted on said standard effective to release said dagger from said lever as the dagger moves forward on its operative stroke.

4. A center filling stop motion for looms comprising a shipper rod, an arm on said rod, a fixed stand, a lever pivoted on said stand and engaging said arm to actuate the shipper, a filling fork and dagger mounted on the lay, said dagger being connected to said filling fork and being adapted to engage and actuate said lever, and a roll rotatable on a fixed pivot on said stand and effective to disengage said dagger and lever with a smooth rolling action at a predetermined point before the dagger reaches its forward limit of travel, such disengagement being caused by the simultaneous forward movement of said dagger and lever past said fixed cam roll.

In testimony whereof I have hereunto set my hand.

JOSEPH A. GAGNON.
